UNITED STATES PATENT OFFICE.

OTTO J. DECKELMANN, OF ST. LOUIS, MISSOURI.

INDEX-TAB.

SPECIFICATION forming part of Letters Patent No. 508,289, dated November 7, 1893.

Application filed November 18, 1892. Serial No. 452,396. (No model.)

To all whom it may concern:

Be it known that I, OTTO J. DECKELMANN, of St. Louis, Missouri, have made a new and useful Improvement in Index-Tabs, of which 5 the following is a full, clear, and exact description.

My improvement relates more especially to the means for protecting, stiffening, and ornamenting an index tab, or analogous construction, substantially as is hereinafter set forth and claimed, aided by the annexed drawings, making part of this specification, in which—

Figure 1 is a face view of a development of 15 the tab; Fig. 2 an edge elevation of the same; Fig. 3 an edge elevation of the tab partly folded; Fig. 4 a view in perspective of the frame, border, or guard which is applied to the tab; Fig. 5 a face view of the tab having 20 the frame applied thereto; Fig. 6 a section on the line 6—6 of Fig. 5; Fig. 7 a section on the line 7—7 of Fig. 5; and Fig. 8 a view showing the improved tab in position upon the leaf.

The same letters of reference denote the 25 same parts.

The tab, A, in itself is of the usual construction, and it is applied to the leaf, B, in the ordinary manner. In the present instance the tab is supposed to be made of an outside, 30 a, of leather or other material suitable for tabs, and an inside, a', of some textile fabric which is cemented to the inner side of the part a for the purpose of strengthening the construction and enabling it to be desirably 35 applied to the leaf.

C represents what may be termed a frame, border, or guard. Its function primarily is to protect that portion of the tab which projects from the leaf from wear. It also 40 serves to materially strengthen the tab, and to preserve its form, and it may be utilized to enhance the appearance of the tab. Its most desirable form is shown. It is composed of any suitable material for the purpose in

question, and preferably of thin sheet metal, 45 and generally one whose color contrasts with that of the tab. It is preferably arranged directly at the edge of the tab as shown, and it is, in the present instance, adapted to the tab by making it in the form of a grooved or folded 50 piece of metal shaped to fit onto the edge of the tab, and it is secured to the tab in any suitable manner and usually by compressing the folds, c, c, of the frame closely onto the faces of the tab, and in providing for the proper 55 connection of the frame with the tab the two parts may have any preferred relative shape so that they may be interlocked, connected, or secured together in any desired manner. The part, C, when thus attached to the tab 60 forms projections upon the faces of the tab which take a large portion of the wear which otherwise comes directly upon the tab in use. The letter, D, or whatever character is upon 65 the tab, is therefore rendered more durable. The frame also aids to preserve the form of 70 the tab, and to keep it in position. When properly applied the frame is made to meet the edge of the leaf, substantially as shown in Fig. 8.

I claim—

1. As a new article of manufacture an index tab for book leaves, provided at the edges of one end with a protecting and stiffening frame, substantially as described.

2. An index tab for book leaves lined on the inside with textile material to enable it to be attached to the leaf, and provided at the end projecting beyond the leaf edge with a strengthening and protecting frame, substantially as described.

Witness my hand this 12th day of November, 1892.

OTTO J. DECKELMANN.
